UNITED STATES PATENT OFFICE

EVERETT P. LARSH, OF DAYTON, OHIO, ASSIGNOR TO THE MASTER ELECTRIC COMPANY, OF DAYTON, OHIO, A CORPORATION OF OHIO

SHORT-CIRCUITING DEVICE FOR MOTOR COMMUTATORS

Application filed January 17, 1921. Serial No. 437,906.

This invention relates to electric motors and more particularly to a short circuiting or operation changing device for alternating current motors of the repulsion-induction type, by which the motor is automatically changed from a repulsion starting condition to an induction running condition and vice-versa in accordance with variations of speed.

The object of the invention is to simplify the structure as well as the means and mode of operation of such circuit changing devices whereby they will not only be cheapened in construction, but will be more efficient in use, automatic in operation, uniform in action, automatically controlled, and unlikely to get out of repair.

A further object of the invention is to provide improved means operated by centrifugal tendency by which the commutator bars are automatically connected with a common electrical conductor which will promptly respond to variations of speed above and below a predetermined rate of rotation.

A further object of the invention is to provide a short circuiting or current changing device, which will have a wiping action insuring perfect electrical contact, in which this wiping action will be further effected under yielding pressure thereby obviating any chatter or vibration and the incident arcing and burning of the contact surfaces.

A further object of the invention is to provide means for controlling the movement of the short circuiting or current changing members whereby their movement to effect the alternation of the motor from repulsion to induction operation and vice-versa will be effected by a quick movement in either direction.

A further object of the invention is to provide such a short circuiting or current changing device which will be compact, of few parts, and having no pivot joints, nor indirect movement, but in which the current controlling devices are directly operated by centrifugal tendency.

With the above primary and other incidental objects in view as will more fully appear in the specification, the invention consists of the features of construction, the parts

and combinations thereof, and the mode of operation, or their equivalents, as hereinafter described and set forth in the claims.

Referring to the accompanying drawings, Fig. 1 is a sectional view of a motor commutator and the short circuiting device forming the subject matter hereof applied thereto. Fig. 2 is an end elevation partly broken away of the short circuiting device and commutator. Fig. 3 is a perspective view partly broken away of the assembled short circuiting device removed from the armature shaft. Fig. 4 is a detail sectional view somewhat diagrammatic illustrating successive positions of the centrifugally operated short circuiting elements. Fig. 5 is a detail perspective view of one of the centrifugally operated contact slugs and a portion of the retaining and retracting band. Figs. 6, 7 and 8 illustrate different modifications of the means for deflecting the contact slug into engagement with the commutator. Fig. 9 is a further modification thereof, wherein yielding spring means is employed. Figs. 10 to 13 illustrate further modifications.

Like parts are indicated by similar characters of reference thruout the several views.

The structure of the electric motor per se, forms no part of the present invention, which pertains wholly to the short circuiting means for the commutator bars, by which the motor is caused to operate alternately as a repulsion motor and an induction motor.

An alternating current, repulsion-induction motor of the single phase type to which the present invention is particularly adapted is one which as the name indicates, starts as a repulsion motor and as the speed approaches its normal or maximum rate or rotation automatically changes its character, and runs as an induction motor. Briefly described it consists of a field or stator of laminated, toothed construction having a single winding thereon connected to the supply circuit and a progressively wound armature or rotor with a commutator engaged by brushes during the starting or "repulsion" period together with speed controlled devices for short circuiting the armature windings thru the commutator after the armature has attained 100

a predetermined speed, which speed controlled means in some instances lifts the brushes from the commutator simultaneously with the short circuiting operation. There is no electrical connection between the stator and the rotor. The currents in the stator create an alternating flux which reacts on the rotor and induces its rotation. This type of motor, therefore, starts as a simple repulsion motor without compensating or auxiliary windings and operates as a repulsion motor until the rotor or armature approaches a synchronous speed or one commensurate with the windings, whereupon the speed controlled devices operate to automatically short circuit the armature winding thru the commutator. Thus the motor is automatically transformed from a repulsion type into an induction motor having what is essentially a squirrel cage rotor. It is the improvement of the speed operated governing or short circuiting device which forms the subject matter of the present invention. One of the advantages of a machine of this type is that it is inherently a constant speed motor having a high starting torque with low current consumption or minimum current surge.

The typical repulsion motor without compensation gives the most efficient starting torque possible while the single phase induction rotor with the squirrel cage armature or its equivalent affords the most efficient motor when running.

A repulsion-induction type of motor combines these most desirable qualities in a single machine. As it possesses such high starting torque characteristics it is well adapted for operating machinery which starts under full load, as pumps, air compressors, grinding mills, etc. Requiring no starter they are adapted for automatic control, or distance operation. They start quickly and operate quietly and smoothly.

The above is offered merely to facilitate a thorough understanding of the purpose of the invention, and with no intent nor desire that it shall in any way be construed as limiting or restricting the application or scope of the invention.

Inasmuch as the construction of the motor per se forms no part of this invention, it has not been illustrated. It is to be understood, however, that the short circuiting means forming the subject matter hereof is applicable to various styles of motors of the character heretofore indicated. Referring to the drawings, 1 is the armature shaft, on which is carried the usual commutator comprising the core 2 about the periphery of which are located a continuous succession of commutator bars 3, insulated from the core 2 and from each other by intervening bodies of insulating material 4. The commutator bars 3 project somewhat beyond the terminal face of the core 2, and are beveled or inclined on their

inner faces as at 5, thereby affording a beveled peripheral flange upon the lateral face of the commutator.

The short circuiting means is embodied in a unitary structure capable of being assembled independent of the motor and applied thereto or removed therefrom without the necessity of disassembling either the motor or the short circuiting means. However, this short circuiting device may if desired be assembled directly upon the motor shaft.

The short circuiting device comprises a sleeve or hub 6, adapted to be secured upon the armature shaft 1, adjacent to the face of the commutator. This sleeve or hub 6, carries fixedly attached thereto, and immovable in relation one with the other, two spaced discs 7 and 8. The larger disc 8 is concave or cup shape affording an inwardly extending peripheral flange overhanging the sleeve or hub 6. These discs 7 and 8 may be secured to the sleeve or hub 6 in any suitable manner. The preferred mode of attachment is to form the hub or sleeve 6 with terminal shoulders or rabbets against which the respective discs 7 and 8 are assembled, and the protruding ends of the hub or sleeve 6 beyond such disc are then upset by spinning, staking or other suitable operation. Intermediate the respective discs 7 and 8 are assembled a plurality of radially disposed bifurcated slugs or contact elements 9. These contact elements or slugs are somewhat wedge shaped or tapered as shown in Figs. 2 and 3, and are assembled side by side to form a continuous band about the hub 6, intermediate the discs 7 and 8. Extending about the assembled series of contact slugs or elements 9 and engaging in the external bifurcations 10 thereof is an endless elastic band 12. This band may be of any suitable or desirable character, but for convenience of manufacture and economy, a helical spring, the ends of which are joined to afford a continuous band of suitable diameter has been employed. In lieu of this type of elastic band, a coiled wire spring, the convolutions of which extend entirely around the assembly of slugs or contact elements may be employed, or several convolutions of a flat spiral spring might be utilized.

The elastic band 12, of whatever character it may be, tends to contact the slugs or contact elements 9 into their innermost position.

The innermost disc 7 and the assembly of contact slugs, or short circuiting elements 9, are of less diameter than the inclined flange 5, formed by the overhanging ends of the commutator bars 3. The short circuiting unit is located upon the armature shaft 1 in juxtaposition to the face of the commutator core 2, with the inclined or beveled ends 5 of the bars overhanging the slugs or contact elements 9, from the inner side of the unit, while the shell or concave disc 8 over-

hangs such contact elements 9 from the outer side and approaches toward, but terminates in spaced relation with the ends of the commutator bars. This short circuiting unit is 5 removably secured upon the armature shaft 1 by a clamp nut 13, between which and the end of the sleeve or hub 6 is interposed a washer 14. The centrifugal tendency induced by the rotation of the shaft 1, and 10 the series of contact slugs 9 carried thereby, tends to move such slugs outwardly against the tension of the elastic contracting band 12. Whenever the centrifugal tendency is sufficient to overcome the tension of the band 15 12 the slugs 9 in their outward movement will engage the beveled face 5 of the overhanging ends of the commutator bar 4, and upon increased centrifugal influence will tend to slide outward upon such inclined faces 20 until they contact with the inner face of the concave disc or shell 8. It is to be noted that the shell or disc 8 is also provided with a beveled face 15. This bevel of the shell or disc 8 is, however, located somewhat more 25 remotely from the center of rotation than the bevel 5 of the commutator bar. That is to say, the slugs will first engage the bevel 5 of the commutator bar and will thence travel along these inclined surfaces in a 30 diagonal direction before engaging the beveled face 15 of the shell or disc 8, whereupon the slugs will wedge themselves in firm contact within the angle formed by the respective bevel faces 5 and 15, as shown by 35 solid lines in Fig. 4. Fig. 4 shows the successive steps in the movement of the contact slugs under centrifugal tendency. In their normal position when the rotor is at rest or before it has attained the predetermined 40 operating speed, these contact slugs will be held in a contracted position as shown by dotted lines, position I. However, as the rotor approaches the predetermined speed at which the operation changes from repulsion to induction mode of operation, the slugs 45 will move directly outward against the tension of the elastic band 12 until they contact the bevel 5 of the overhanging commutator bar as shown by dot and dash lines, 50 position II. Further increase of speed induces greater centrifugal influence, and the beveled face 5 of the commutator bars will have a camming action by which the slugs in their outward movement are deflected 55 laterally, thus affording a wiping or rubbing contact between the slugs and the beveled face 5 of the commutator bar, until the slugs finally come to rest in engagement with the 60 retaining shell or disc 8. This wiping or rubbing action induced by the diagonal movement of the slugs upon the beveled face 5 from the position II to the position III of Fig. 4 insures a bright, clean contact surface, and automatically insures perfect electrical engagement.

While the assembly of contact slugs 9 about the hub or sleeve 6 and intermediate the discs 7 and 8 will normally rotate in unison therewith independent of any driving engagement, and moreover, any independent 70 rotation or slippage of the assembly of slugs in relation with the discs and hub would be immaterial, there have been shown in Figs. 2 and 3, driving vanes 16, projecting inwardly from the disc 7 intermediate the slugs 9. 75

There may be any number of these vanes provided as may be desired. In practice three or four of such vanes have been found amply sufficient. These vanes 16 in the illustrated construction comprise merely tongues 80 or flaps of metal, stamped from the disc 7 at spaced intervals and protruding between successive slugs of the series, dividing the contact slugs into a plurality of groups and affording a positive driving connection between the assembly of slugs and the carrier therefor. In lieu of this construction, the hub or sleeve 6 may be slotted and driving vanes 17 may be inserted and secured within such radial slots shown in the detail view 90 Fig. 10.

If so desired, the disc 7 may be entirely omitted, and the slugs may rest in direct contact with the terminal face of the commutation core 2. 95

Under ordinary conditions of usage, the yielding resistance of the elastic band 12 may be relied upon to afford definition to the movements of the contact slugs. The slugs will not tend to move until the centrifugal influence due to increased speed is sufficient to overcome the tension of the band 12. The initial outward movement of the slugs against the tension of the band materially increases their tendency to move further under centrifugal influence thru the fact that with each degree of movement their distance from the center of rotation is increased, and hence the centrifugal influence accelerated. This in itself is sufficient to induce a quick movement into and out of operative position. However to afford further definition to this movement, the contact slugs 9 may be caused to tilt or incline within the carrier toward the commutator and thus have a frictional bearing upon the face of the commutator core 2 or upon the interposed retaining disc 7 as the case may be, which must be overcome in addition to the retractive influence of the elastic band 12. To this end, the hub or sleeve 6 100 may be tapered or inclined as shown in Figs. 4 and 6, whereby the slug 9 engages the hub or sleeve while at rest, only at a remote point beyond the plane of the elastic band 12, the contraction of which tends to oscillate the slug about its contact point with the hub, inwardly against the commutator or the disc 7, thereby affording a frictional contact or bearing. In Fig. 7, the hub or sleeve 6 is inclined 105 in the opposite direction to form a peripheral 110

groove 18, in which engages a projecting finger or corner 19 of the slug to form a fulcrum upon which the retractive band 12 tends to tilt the slug 9 inwardly. The peripheral groove 18 is of such extent that the fulcrum point will be guided outwardly by the cam action of the groove, as the slug is retracted under the influence of the band 12. At the same time the outer or bifurcated end of the 10 slug will be tilted toward the commutator. In Fig. 8 the inner edge of the slug and the hub or sleeve have both been inclined in the same direction, so that the retractive action of the elastic band 12 tends to slide the slug 15 9 down the inclined or tapered face of the hub or sleeve 6 into frictional contact with the face of the commutator. In Fig. 9 a spring disc or series of spring fingers 20 secured to the inner face of the shell or disc 8 20 serve to yieldingly press the slugs toward the commutator. In these constructions the centrifugal influence must first overcome the frictional engagement of the slug with the disc 7 or the face of the commutator, tending 25 to straighten the slug upward before it begins its outward travel against the tension of the elastic band 12. It will be understood that the disc 7 may be employed or omitted as is found most desirable or convenient. How- 30 ever, by employing the disc 7, the short circuiting mechanism may be independently assembled, and interchangeably employed upon different motors, or shipped to distant points for substitution.

35 In Fig. 13 there is shown a modification wherein in lieu of the driving vanes 16 or 17, certain contact slugs at spaced intervals in the series are provided with outwardly extending wings 22 which engage and slide in 40 radial slots 21 in the discs 7 and 8. It will be understood that only a few of the contact slugs will be so engaged in the discs, the remaining slugs being as shown in the other figures.

45 From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

55 While in order to comply with the statute the invention has been described in language more or less specific as to structural features, it is to be understood that the invention is not limited to the specific details shown, but 60 that the means and construction herein disclosed comprise but one of several modes of putting the invention into effect and the invention is therefore claimed in any of its forms or modifications within the legitimate 65 and valid scope of the appended claims.

Having thus described my invention, I claim:

1. In a short circuiting means for commutators, a commutator having a peripherally arranged series of commutator bars, a series 70 of independent bifurcated contact slugs arranged in a concentric circular series in proximity to the lateral face of the commutator and slidably radially thereon into engagement with the commutator bars, and an elastic band engaging in the bifurcations of the slugs against the tension of which the series of slugs is expanded by centrifugal influence and means engaged by the slugs during their radial movement for laterally deflecting the slugs to insure lateral wiping contact with the commutator bars. 80

2. In a short circuiting device for commutators, a circular series of independent polygonal slugs having registering notches forming a peripheral groove in the assembled circular series of slugs, an elastic retaining band engaged in said groove, said circular series of slugs being concentrically disposed in juxtaposition to the lateral face of the 90 commutator and radially expansible under centrifugal influence and a cam face in the path of radial movement of the slugs engaged thereby as they approach the limits of their radial movement by which they are laterally urged to insure a wiping electrical engagement with the commutator bars. 95

3. In a short circuiting device for commutators, a disc fixedly mounted in parallel spaced relation with the commutator, converging spaced flanges upon the commutator and disc respectively, the inner circumference of the disc flange being of greater diameter than that of the commutator flange, and a series of centrifugally actuated weights 100 loosely interposed between the commutator and disc adapted to initially engage the commutator flange under the influence of centrifugal force and slide thence upon the inclined flange of the commutator into engagement with the disc flange. 105

4. In a construction of the character described, a commutator, a disc fixedly mounted in parallel spaced relation with the commutator, one of said members having a flange inclined to the axis of rotation and extending toward the other member, a series of centrifugally actuated weights loosely interposed between the commutator and disc and radially movable under centrifugal influence and adapted to engage the inclined flange as they approach the limit of their radial movement thereby being laterally deflected into wedging engagement with the other member. 115

5. In a construction of the character described, a commutator having a peripherally disposed series of commutator bars, a disc fixedly mounted in parallel spaced relation with the commutator, a series of centrif- 125

- ugally actuated weights loosely interposed between the disc and commutator, an elastic band against the tension of which the weights are radially movable under centrifugal influence into electrical engagement with the commutator bars, said commutator bars being beveled for laterally deflecting the weights by their engagement therewith during their radial movement.
6. In a unitary short circuiting device for commutators, a spool like carrier comprising a hub sleeve and parallel spaced discs secured thereto, a series of contact slugs interposed between the discs, and vanes carried by said spool separating the series of slugs into groups and affording positive driving connection therefor, said spool carrying the contact slugs being immovably mountable in juxtaposition to the lateral face of a commutator the bars of which are engaged by the slugs when distended by centrifugal influence.
7. In a short circuiting device for commutators, a circular series of independent contact slugs concentrically arranged in juxtaposition to the lateral face of the commutator and controlled by centrifugal influence, means for effecting a tilting movement of the slugs as they approach the limit of their retractive movement, and a guide member frictionally engaged by the tilted slugs to afford temporary resistance to their radial movement under centrifugal influence.
8. In a short circuiting device for commutators, a commutator having a peripherally disposed series of commutator bars, a disc located in parallel spaced relation with the lateral face of the commutator, a circular series of independent contact slugs concentrically arranged relative thereto and confined between said disc and the lateral face of the commutator and controlled by centrifugal influence, yielding retracting means for said slugs, and a fulcrum seat for the slugs at the inner limit of their movement laterally offset relative to the plane of influence of the retracting means whereby the slugs will be laterally tilted when in their retracted positions.
9. In a short circuiting device for commutators, a circular series of independent contact slugs concentrically arranged in juxtaposition to the lateral face of the commutator and capable of both radial and lateral shifting movement, said slugs being movable radially into engagement with the commutator bars by centrifugal influence, a guide for said slugs, and means for deflecting the slugs laterally into frictional contact with their guide to afford a supplemental frictional resistance to their radial movement under centrifugal influence.
10. In a short circuiting device for commutators, a disc fixedly mounted in parallel spaced relation with the commutator, contact slugs concentrically arranged intermediate the disc and the lateral face of the commutator and capable of both radial and lateral shifting movement independent of said disc, an elastic band against the tension of which the series is capable of distention under centrifugal influence, commutator bars having beveled ends overhanging the contact slugs and engaged thereby in their radial movement under centrifugal influence, said slugs being deflected laterally thru a sliding movement until arrested by said disc between which and the beveled bars the slugs have a wedging engagement.
11. In a short circuiting device for electric motors, a commutator including a series of commutator bars to be electrically interconnected, a disc located in parallel spaced relation with the commutator, an annular series of centrifugally actuated contact members confined intermediate the disc and the lateral face of said commutator, an annular contractile band against the tension of which the contact members are radially movable, under centrifugal influence, and means for effecting a tilting movement of the contact members laterally toward the commutator incident to their radial movement.
12. In a short circuiting device for electric motors, a commutator including a series of commutator bars to be electrically interconnected, a disc located in parallel spaced relation with the commutator, an annular series of centrifugally actuated contact members confined between the disc and the lateral face of said commutator, an annular contractile band concentrically arranged exteriorly of said contact members, and camming means by which the contact members are laterally deflected in engagement with the commutator bars in addition to their radial movement.
13. In a short circuiting device for commutators, a series of commutator bars to be interconnected, a disc mounted in fixed relation with the commutator, an annular series of independent centrifugally actuated contact elements mounted in juxtaposition to the disc, an annular contractile band against the tension of which the series of contact member is expanded into engagement with the contact bars by centrifugal influence and interengaging means between certain individual contact members and the disc permitting relative radial movement, but limiting relative circumferential movement of the contact members and disc.
14. In a short circuiting device for commutators, a series of commutator bars to be interconnected, a disc mounted in fixed spaced relation with the commutator, an annular series of independent centrifugally actuated contact elements interposed between the commutator and disc, an annular contractile band against the tension of which the series of contact member is expanded into

- engagement with the contact bars by centrifugal influence, and means for preventing circumferential movement of the contact members in relation with the disc but permitting relative movement thereof in a radial direction.
15. In a short circuiting device for motors, the combination with a circular series of commutator bars having an interiorly beveled surface, a concentric series of centrifugally actuated contact members, and a yielding restraining means for said members against the tension of which the circular series of contact members is actuated by centrifugal influence into engagement with the bevelled interior surface of the circular series of commutator bars, said members being adapted to ride outwardly upon the beveled interior surface of the commutator bars under centrifugal influence upon acceleration of the motor speed, and a limiting stop for said contact members located in the path of radial movement of said contact members in spaced relation with the commutator bars, and engaged by the contact members at the limit of their radial movement, while maintaining their engagement with said bars.
16. The combination with a circular series of commutator bars having a beveled interior surface, a series of centrifugally controlled contact members and yielding restraining means common to the contact members against the tension of which the said members are movable radially into engagement with the beveled interior surface and a limiting stop in spaced relation with the commutator bars engaged by said contact members by further movement and in continued outwardly inclined direction under centrifugal influence while in sliding engagement with the beveled interior surface of the commutator bars to interconnect the bars one with another.
17. In a short circuiter for commutators, a disc fixedly mounted in spaced parallel relation with the commutator, the adjacent faces of the disc and commutator being convergent one toward the other, a short circuiter for the commutator bars comprising an annular series of centrifugally actuated weights confined for radial movement between the disc and commutator, and an annular contractile band exteriorly surrounding the weights against the tension of which the weights are radially movable under centrifugal influence to expand the band, the radial expansion of said short circuiter serving to electrically interconnect the disc and commutator bars to connect the bars electrically one to another.
18. In a short circuiter for commutators, a disc mounted in fixed parallel spaced relation with the commutator the adjacent faces of the disc and commutator converging one toward the other, an annular expansible and contractile short circuiting device including a series of weights confined for radial move-
- ment intermediate the disc and commutator and an elastic contractile band circumferentially surrounding the series of weights, said short circuiting device being radially expandable by centrifugal influence into wedging engagement with the adjacent converging faces of the commutator and disc.
19. In a short circuiting mechanism for single-phase, alternating current motors and in combination with the armature and commutator thereof, cooperating weight and spring elements operable radially relative to the armature shaft one of which is electrically conductive and adapted to be moved slidably in a radial direction into wiping contact with the lateral face of the commutator to effect short circuiting of the armature, and means whereby said contact is made with increasing pressure as the weights move outwardly.
20. In short-circuiting mechanism for single-phase, alternating current motors and in combination with the armature and commutator thereof, a plurality of radial centrifugal elements arranged in substantially equal groups circumferentially of the armature shaft and retained axially thereon by a disc having a series of radial slots, certain of said elements being operable in said slots and acting to retain the elements of each group as to lateral displacement thereof, and a spring element arranged circumferentially and operable radially with the centrifugal elements.
21. In short-circuiting mechanism for single-phase, alternating current motors and in combination with the armature and the commutator thereof, a plurality of radial centrifugal elements arranged circumferentially of the armature shaft and retained axially thereon by a disc supported on the armature shaft and having a series of radial slots, certain of said elements being operable in said slots and acting to retain the elements of each group as to lateral displacement thereof, and a spring element against the yielding resistance of which the centrifugal elements are radially movable into engagement with the commutator segments, said elements being subjected to resistance by said disc at an angle to their said radial movement whereby pressure is provided for establishing wiping contact between said centrifugal elements and the commutator segments.
22. In short-circuiting mechanism for single-phase, alternating current motors and in combination with the armature and the commutator thereof, a plurality of radial, wedge-shaped centrifugal elements arranged in groups circumferentially of the armature shaft and retained axially thereon by a disc mounted on said shaft and having a series of radial slots, other radially disposed elements interposed between the groups of the wedge-shaped elements and engaged in said slots to retain the elements of each group as to lateral displacement thereof, and a spring

element arranged circumferentially and operable radially with the centrifugal elements against the yielding resistance of which the centrifugal elements are movable for establishing contact between said centrifugal elements and the commutator segments.

23. In a short circuiter for electric motors and the like, the combination with an armature and commutator, of a series of centrifugally actuated weights arranged circumferentially of the armature shaft and operable substantially radially relative thereto, a spring element co-acting therewith and yieldingly resisting their movement under centrifugal influence, and a disc located contiguous to the said weights having therein radial slots defining the paths of movement of the weights.

24. In a short circuiter for electric motors and the like, the combination with an armature and a commutator, of a plurality of centrifugally actuated weights located at spaced intervals about the armature shaft and movable substantially radially relative thereto, an annular helical spring band exteriorly surrounding the weights and yieldingly resisting their outward movement, and a slotted guide disc located contiguous to said weights within the slots of which the weights project and defining the paths of movement of said weights to effect the short circuiting of the armature windings.

25. In a short circuiting device for electric motors and the like, the combination with an armature and a commutator, of a series of centrifugally actuated weights disposed in different radial positions about the armature shaft and movable substantially radially relative thereto, a spring tension member circumferentially surrounding the weights against the tension of which the weights are movable to effect the short circuiting of the armature windings, and guide means for said weights directing their movement toward and from the armature shaft.

26. In a short circuiting device for electric motors and the like, the combination with an armature and a commutator, of a series of centrifugally actuated weights disposed in different radial positions about the armature shaft and movable substantially radially relative thereto, an annular helical spring band exteriorly surrounding the weights, and a disc with which the weights have engagement at spaced intervals to insure unison rotation with the armature and to guide said weights in their to and fro movement relative to the armature shaft to effect the short circuiting of the armature windings.

27. In a short circuiting device for electric motors and the like, the combination with an armature and commutator, of a series of weights arranged circumferentially and operable radially relative to the armature shaft and an annular helical spring band exterior-

ly surrounding the weights against the yielding resistance of which the weights are movable into and out of contact with the commutator segments and a deflecting surface engaged by the weights as they approach the outward limit of their radial movement whereby said contact is effected with increasing lateral pressure as the weights move outwardly.

28. A short circuiter for electric motors, the combination with a commutator, a plurality of weight elements arranged circumferentially of the commutator shaft and movable in radial directions under centrifugal influence into short circuiting engagement with said commutator, said weights having therein registering marginal indentations forming a seat for a retractile spring and a helical spring, the ends of which are interconnected into an annular band having seating engagement in the registering indentations of the weight elements against the yielding resistance of which the weight elements move under centrifugal influence to effect short circuiting of the commutator.

29. A short circuiting device for electric motors including in combination with a commutator an annular series of contact members subject to centrifugal influence and movable thereby in radial directions into short circuiting contact engagement with the commutator, said contacts being notched in their outer edges to form a seat for a retractile spring and a helical spring having its ends interconnected into annular formation seated in the registering notches and yieldingly resisting the movement of the contact members into engagement with the commutator under centrifugal influence.

In testimony whereof, I have hereunto set my hand this 15th day of January, 1921.
